UNITED STATES PATENT OFFICE.

ORA E. STRAWN, OF BOISE, IDAHO.

EMBOSSING-MACHINE.

1,207,091.

Specification of Letters Patent.

Patented Dec. 5, 1916.

Application filed March 4, 1915. Serial No. 12,156.

To all whom it may concern:

Be it known that I, ORA E. STRAWN, a citizen of the United States, residing at Boise, in the county of Ada and State of Idaho, have invented new and useful Improvements in Embossing-Machines, of which the following is a specification.

My invention relates to embossing machines of the type suitable for use in connection with the Crimp process for embossing in which a fusible powder is dusted onto a freshly printed surface, the ink of which is not yet dry, so as to cause the powder to adhere to the ink, after which heat is applied, thus affecting the molecular condition of the powder and causing the printed letters to apparently swell, and at the same time harden.

By my improved apparatus, I seek to facilitate the performance of the different steps of the process referred to.

My apparatus is used in connection with a printing press, say, a job press, and operates upon the sheets one at a time as they are received from the press. Each sheet is by my device taken up, and placed in a position to receive the fusible powder. The powder is then dusted on by action of special mechanism for the purpose, the excess of powder being removed by action of compressed air and properly taken care of; the sheet being then subjected to the action of heat for a moment, and finally transferred to a jogging board, and there brought into registry with other sheets similarly treated.

My invention further comprehends means for taking care of charges of the fusible powder under conditions where, owing to the occasional skipping of a sheet by the press or by the press feeder, it happens that no sheet is in position ready to receive the powder at the time when the charge of powder would otherwise be thrown upon the sheet.

My invention also includes means for turning the sheet in some instances, and especially if the sheet be in the form of an envelop, or if for any other reason it happens that the heat should be applied to the face of the sheet rather than to the back thereof.

My invention also contemplates various improvements in mechanism of this general character, for improving its efficiency.

Reference is made to the accompanying drawings, forming a part of this specification,

tion, and in which like letters indicate like parts.

Figure 1 is a plan view of my embossing machine complete, together with parts immediately associated with it. Fig. 2 is a vertical section on the line 2—2 of Fig. 1, looking in the direction of the arrow. Fig. 3 is a side elevation of the machine, as seen by a person standing at the left of Fig. 1, and looking toward the machine as therein shown. Fig. 4 is a fragmentary section on the line 4—4 of Fig. 1, looking in the direction of the arrow, and showing a portion of the powder feeding mechanism. Fig. 5 is a horizontal section on the line 5—5 of Fig. 4, looking in the direction of the arrow, and showing the discharge outlet for the powder. Fig. 6 is a detail view, showing a slide used for periodically opening and closing the discharge outlet for the powder. Fig. 7 is a plan view of certain gearing and other mechanism shown at the left of Fig. 4, and used for controlling the discharge of the powder. Fig. 8 is a vertical section on the line 8—8 of Fig. 7, looking in the direction of the arrow. Fig. 9 is a perspective showing a bracket used as a part of the mechanism in Fig. 8. Fig. 10 is a fragmentary side elevation showing certain mechanism appearing at the left of Fig. 8, and used for controlling certain gearing and other parts for actuating the movement of the powder. Fig. 11 is a fragmentary end elevation of the mechanism shown in Fig. 10 and at the left of Fig. 3. Fig. 12 is a detail view, showing the heating mechanism and means for supplying gas thereto. Fig. 13 is a section on the line 13—13 of Fig. 12, looking in the direction of the arrow. Fig. 14 is a fragmentary vertical section, on the line 14—14 of Fig. 3, looking in the direction of the arrow. Fig. 15 is a detail view, showing in side elevation a part of the mechanism for turning an envelop or the like, after the same has been dusted with the fusible powder.

While my apparatus may be applied to different kinds of printing presses, I will for convenience describe it as applied to any well known form of job press, having its fly wheel located upon the left hand side of the press, and which is also provided with a feed board, or feed tables.

The feed board of the press appears at 16, and at 17 is the fly shaft. Mounted rigidly upon the fly shaft and driven thereby, is the fly wheel 18 of the press. Upon the fly

shaft 17 I mount a pulley 19, and connect with this pulley a belt 20, driven by it, and leading to an air pump 21 which it thus actuates.

5 The frame of my embossing machine is shown at 22. Journaled within this frame is a revoluble shaft 23, and carried by the latter is a gear wheel 24. This gear wheel is splined to the shaft 23, and therefore 10 adapted to slide in the general direction of the length of this shaft, as well as to turn with the same. The gear wheel 24 is provided with a hub 25, fashioned into a collar, and engaged by a hand lever 26, in such 15 manner that by rocking the hand lever, the gear wheel 24 is shifted relatively to the shaft 23. The hand lever is pivotally mounted upon a bracket 27.

The shaft 23 carries a bearing 28, having 20 the proximate form of a spool, and mounted upon this bearing is a link 29, provided with a slot 30, and having generally the form of a latch. The shaft 17 of the press carries 25 a spool-like bearing 32, which may be engaged by the link 29, as indicated in Fig. 1. When the parts are thus in engagement, the link 29 serves as a frame connection from the shaft 17 of the printing press to the shaft 23 of the embossing machine. The 30 gear pinion 33, mounted rigidly upon the shaft 17, is adapted to engage and actuate the gear wheel 24, as the hand lever 26 is shifted in its two directions of movement, as will be understood from Fig. 1. With 35 the lever 26 occupying the position indicated in this figure, the gear wheel 24 is out of engagement with the gear pinion 33, and the shaft 17 of the press, in turning, has no effect upon the mechanism of the embossing machine. If, however, the hand lever 26 be shifted in a clockwise direction 40 so as to bring the gear wheel 24 into engagement with the gear pinion 33, the embossing machine is as a whole brought under control of the printing press and thrown into 45 action.

Mounted rigidly upon the shaft 23 is a sprocket wheel 34; and engaging this sprocket wheel is a sprocket chain 35, the latter also engaging a sprocket wheel 36 located adjacent one end of the embossing machine, and mounted rigidly upon a shaft 37. A revoluble drum is also mounted rigidly upon this shaft, and extends across the machine. Engaging the 55 drum 38 are conveyer tapes 39 and 39^a together with supporting wires 39^b all engaging a large roller 40. This roller is mounted rigidly upon a shaft 41, the ends of the roller being engaged by bent portions 60 42 of sprocket chains 43, extending lengthwise of the machine. These sprocket chains engage two sprocket wheels 44 which are rigidly secured to, and virtually form a part of, the drum 38. A jogging board is shown 65 at 45, and supported by the frame 22. This

jogging board may be of the usual or any desired construction.

A conveyer is shown at 46 and is provided with a number of endless bands 47 which run on rollers 48 and 49. In order to actuate these bands, I provide gearing 50 (see Fig. 2) which turns a shaft 51. Engaging this shaft are four driving belts 52, 53, 54 and 55. The belts 52, 53, 54 engage rollers 56 of which there are three pairs, as indicated in Fig. 1. The belt 55 engages a small pulley 55^a, and the rotation of this pulley causes the roller 49 to turn, so as to drive the bands 47.

I provide a guide 57, disposed parallel 80 with the rollers 56, and extending slightly higher than the same. The guide 57 is for the sheets of stock to lodge against, in order to render their position true, accurate, and definite. Two other guides are shown at 59 85 and 60, these being cross bars which also serve as bearings for supporting the rollers 56.

Mounted upon the frame 22 is a platform 61, and over this platform is a powder container 62. This powder container is provided with a portion 63 having a wedge-shaped bottom 64 which normally rests within a hopper 65, the latter being open at its lower end. The portion 64 of the container is made preferably of a single sheet 90 of brass or other resilient metal, the sides not being joined in any way, but spring so that their natural tendency is to come together at their lower edges when not forced apart by wedges 67, thus being provided at 95 its bottom with a slot 66, which is adapted to open and close. That is to say, when the container is removed from its mountings the slot 66 closes, but when the container is in position upon the machine the slot 66 is open.

I provide the two wedges 67 for the purpose of opening the slot 66 and holding it open when the bottom 64 is lowered into 110 65. These wedges are spaced some distance apart, as indicated in Figs. 4 and 5, and between the wedges are a number of feed paddles 68, 69, the latter being mounted 115 upon a feed shaft 98, which extends through the lower portion of the hopper 65. The feed paddles may, if desired, be constructed of sheet metal, stamped or cut out in a single piece and bent into shape.

A slide 71 (see Fig. 4) extends into the 120 container, and serves the purpose of a partition. Engaging opposite faces of this slide are two cushions 71^a, 71^b, for providing a neat fit between the slide and adjacent parts, and rendering the upper compartment substantially air-tight. Normally a quantity of powder within the container 62 rests upon the slide 71, and by pulling this slide partially out the powder may be passed 125 into the lower portion of the container. I 130

designate the space above the slide 71 as the upper compartment, and space below this slide as the lower compartment, of the container.

5 Mounted upon opposite sides of the portion 63 of the container are bearings 72, and journaled in these bearings are two stirrups 73. Carried by these stirrups are two cams 74, which rest upon shelves 75 and are provided with lever handles 76; the cross bar of the stirrups passes through the cam 74 at one side of its center so that said cams turn eccentrically and thus bind against the shelves 75. By turning these handles the 10 upper and lower members of the container are gripped tightly together, so as to clamp the slide 71, or separated, so as to disengage this slide, as the case may be.

15 Mounted upon the lower edge of the hopper 65, and disposed parallel with each other, are two rails 77 which are rigid in position. Slidably engaging the rails is a slide 78, of the form indicated in Fig. 6. This slide is provided with a pair of longitudinal flanges 79, disposed parallel with each other and adapted to fit over the rails 77. The slide 78 is provided with an opening 80, and with a pair of racks 81 disposed upon opposite sides of the flanges 79 and the opening 80. Mounted rigidly upon the shaft 70 are two gear wheels 82, which mesh with the racks 81 when the slide 78 is mounted in position upon the rails 77. As the shaft 70 rotates back and forth, the slide 78 is moved backward and forward relatively to the container, and the feed paddles 68 and 69 are turned in accordance with rotary movements of the shaft.

20 Mounted upon one end of the shaft 70 is a gear wheel 83, located adjacent to a bearing 84 which supports one end of the shaft 70, the other end thereof being journaled in the frame.

25 A rack 85, movable in the general direction of the length of the frame 22, engages and rests upon the gear wheel 83. A leaf spring 86 is carried by a flange 87 forming a part of a bracket 88, the latter being supported by a cross bar 89, which is shown in Fig. 7 by dotted lines. The leaf spring 86 is partially disposed within the path of travel of the rack 85, and is adapted to be actuated by this rack, so as to rock the bracket 88. This bracket carries a pair of 30 spring fingers 88^a which extend downwardly and engage opposite sides of a shaft 90, so as to serve as a bearing for this shaft. Another bearing 91 engages the shaft just mentioned, and is carried by the frame work. 35 A sprocket wheel 92 is mounted rigidly upon the shaft 90, and engages the sprocket chain 43, whereby it is driven.

40 A gear wheel 94^a, located near the sprocket wheel 92, (see Figs. 7 and 8) is supported by aid of a bracket 95, this bracket being

provided with extending portions 95^a, 95^b, and mating the portion 95^b is a bracket member 96. The wheel 94^a is mounted rigidly upon a shaft 97, and meshes with a gear pinion 99, which is mounted rigidly upon a shaft 98. This shaft, by its rotation, turns the feed paddles 69, and thus causes the powder to pass downwardly from the container, and rotation of the shaft 98 is accomplished by shaft 70 through the various gear elements as will be now more fully set forth.

45 As the rack 85 is moved backward and forward, the leaf spring 86 is alternately placed under tension and released, so that the bracket 87 is rocked slightly. For this purpose the bracket is mounted upon a pivot pin 100 carried by the bar 89. Each time the spring 86 is placed under tension by the rack 85 moving bodily endwise in the direction of the spring, the gear 101 is shifted into mesh with the gear 102, so that the shaft 98 rotates, and the feeding mechanism is thus thrown into operation. Each time the rack 85 moves in the reverse direction, however, the gear 101 is unmeshed from the gear 102 and the shaft 98 stops turning, the feeding mechanism thus being rendered idle. The shaft 98 therefore rotates intermittently in a single direction. Each time the shaft 50 70, by its rocking movement, causes the slide 78 to close the lower end of the hopper 65, the shaft 98 momentarily stops turning. Every time the slide 78 opens the lower end of the hopper, the shaft 98 starts to turn, so that the powder is fed downwardly so long as the hopper remains open.

55 A leaf spring 103 is used for normally holding the shaft 90 in such position that the gear 101 is out of mesh with the gear 105 wheel 102.

60 In order to actuate the rack 85, I provide a connecting rod 104, secured to it by a pivot pin 105. The connecting rod 104 is secured by another pivot pin 106 to the upper end 110 of an arm 107, this arm being secured rigidly upon a rocking shaft 108, which is journaled in bearings 109.

65 Mounted rigidly upon the shaft 108 and extending downwardly from the same is an arm 110. Mounted loosely upon the shaft 108 is another arm 111. Connected with the lower end of the arm 110, by means of a pivot pin 112, is a slide bar 113. Parallel with the slide bar 113 is another slide bar 113^a which is pivoted to the arm 111. The slide bars 113, 113^a are of the form indicated in Fig. 10, and provided with a slot 114. A guide pin 115 extends through these slots, and is secured rigidly to the frame work. 120 The slide bar 113 carries an arm 116, and the slide bar 113^a carries a somewhat shorter arm 117. These two arms are provided with downwardly extending pins 118, 119. Secured rigidly to the bar 113, and extending 125

BEST AVAILABLE COP

1,207,091

downwardly from the same, is a bar 120. Similarly a bar 121 is secured rigidly to the bar 113^a, and extends downwardly from the same. Near the bottom ends of these bars 5 120, 121 they are provided with arms 122, 123, carrying pins 124, 125, as indicated in Fig. 11.

Mounted upon the frame work, adjacent the lower ends of the bars 120, 121, is a 10 bracket 126. The lower ends of the bars 120, 121 are provided with guide pins 127, which extend through slots 127^a in bracket 126.

Mounted rigidly upon the drum shaft 37 is a cam wheel 128, located outside of the 15 frame work, as indicated in Figs. 10 and 11. The cam wheel 128 carries on its peripheral surface a plate 128^a, having the general arcuate form and provided with projecting bosses 129 and 130. The plate 128^a is further provided with two slots 131, staggered slightly in relation to each other, and extending through these slots are screws 132 whereby the plate is held in position upon the cam wheel 128, and is rendered adjustable 20 relatively to the same. The cam wheel carries another plate 128^b, somewhat similar to the plate 128^a, and provided with two bosses 133 and 133^a. As the drum shaft 37 is turned, the cam wheel 128 rotates continuously, so that the bosses 129, 130 engage the pins 119, 118, thus moving the bars 113, 113^a to the left according to Fig. 10. Then the bosses 133, 133^a, engage the pins 124, 125, and cause the bars 113, 113^a to move 25 to the right according to Fig. 10.

As the plates 128^a, 128^b are diametrically opposite each other upon the cam wheel 128, and as the pins 124, 125 are not quite diametrically opposite the pins 118 and 119, 30 the bars 113 and 113^a remain most of the time in their extreme position to the right according to Fig. 10, and dwell for a comparatively short time in their position to the left according to said figure. That is 35 to say, according to Fig. 10, the shaft 108 rocks first in a clockwise direction and quickly afterward rocks in a counter-clockwise direction, and then remains stationary for a comparatively long period of time, representing approximately the time required for the cam wheel 128 to make 40 half a revolution. The rocking of the shaft 108 controls the movements of the connecting rod 104, rack 85, and shafts 70 and 98, 45 and through these members controls the distribution of the powder from the container. The net result is that at intervals the lower end of the hopper is opened and then quickly closed, and during the time while 50 the hopper remains open, the feed paddles cause the discharge of a small quantity of the powder.

The arm 111, carried by the rocking shaft 108 (see Figs. 3 and 10) extends through 55 a slot 134 in a sliding bar 135, this bar

being supported by slideway brackets 136. The sliding bar 135 is connected rigidly with a rod 135^a, the latter thus virtually forming a continuation of the bar in question, and with it used, as hereinafter described, in connection with control of the air supply.

I provide three doors 137, 137^a, 137^b, for protecting various parts and rendering them readily accessible. These doors are mounted 70 upon hinges 138. The door 137 is provided with two hand holes 139 and 140.

The heating mechanism—that is, the burner mechanism and parts associated therewith for heating the sheets—is shown 75 more particularly in Figs. 12 and 13.

A bracket 141 is fixed rigidly to the frame work, and supports a bearing 141^a. Mounted within this bearing is a shaft 141^b, carrying a hand wheel 144. Mounted rigidly upon the shaft 141^b is a gear wheel 143. Meshing with this gear wheel is a rack 142^a, carried by a sleeve 142. By turning the hand wheel 144 the sleeve 142 is raised or lowered. Extending through the sleeve 90 142, and secured rigidly to the same, is a burner tube 145 connected with a flexible gas tube 146. The burner tube 145 carries a valve 147 provided with a hand wheel 148 whereby it is operated. The burner tube also carries a bulb 149, provided with air inlet holes 150. The burner tube also carries a T 151 supporting two longitudinal burners 153, disposed parallel with each other.

The operator by turning the hand wheel 148, regulates the supply of gas, and by turning the hand wheel 144 the burners may be raised or lowered relatively to the stock. The burners are covered by a hood 105 153^a, for distributing the heat uniformly. This hood is provided at its top with a glass window 153^b, through which the stock may be observed. The hood acts somewhat as an oven. It holds the heat down upon the 110 stock.

Two pipes 154 and 155 lead from the air pump 21 to the embossing machine. The pipe 155 is connected with a pipe 156, the latter communicating with a pipe 156^a, and this pipe 156^a carries an air nozzle 157.

An air funnel 158 is connected with a pipe 159, leading to the upper portion of the powder container 62. Below the powder container is a funnel 160, which is connected by a pipe 161 and a valve 162 with the pipe 159. Between the funnel 158 and the adjacent portion of the pipe 159 is a valve 163. Between the pipes 156 and 156^a is another valve 164.

A valve shaft is shown at 165 (see Fig. 14) and is by pivot pins 166 connected with the revoluble members 166^a of the valves 163 and 164. The valve shaft 165 carries an arm 167, the latter being provided with 130

a slot 168, through which the rod 135^a extends. This rod, by its longitudinal or thrust movements, rocks the arm 167 and the valve shaft 165, so as to open and close the two valves 163 and 164. By this means the valves just mentioned are actuated by the action of the wheel 128. The valves 163 and 164 are actuated by movements of the sliding bar 135, the latter being carried in the direction of its length by the rocking of the arm 111, this arm being actuated by the bar 113^a.

The parts are so arranged and proportioned as to allow the paper to travel, after receiving the powder, to the point where the compressed air is applied. A pipe 169 leads downwardly from the top of the container 62, and is connected with the pipe 155. A skeleton frame 169^a, mounted upon the pipe 169, extends into the container, and carries a gauze member 169^b, and a piece of felt 169^c, these parts constituting a screen to prevent the powder from entering the pump.

Compressed air is supplied from the pump 21 through the pipe 154, and rarefied air is drawn into the pump from the pipes 169, 155. Since the valves 163 and 164 periodically open and close, as above described, the air supply is intermittent. When compressed air is being discharged from the nozzle 157, air is flowing into the funnel 158. Air also flows into the funnel 160 whenever the valve 162 is opened, thus taking up the powder that has accumulated there.

After a printed sheet is fed into the machine and passes beneath the powder container 62, so that a small charge of powder is deposited upon it, the compressed air from the nozzle 157 removes all excess of powder thus deposited, and such excess is carried into the funnel 158, and thence drawn upwardly through the pipe 159 into the upper portion 45 of the powder container 62. The powder now lodges upon the slide 71 or partition, and thus remains until, by drawing out the slide 71, the powder is let down into the lower portion of the container.

In order to produce and maintain a partial vacuum in the upper portion of the container 62, a partial vacuum is constantly maintained in the pipe 169, by action of the air pump 21. This pipe, by its suction upon the air within the container, is unable to carry any of the powder along with it, because of the pipe being screened by the parts 169^a, 169^b and 169^c, as above explained.

In embossing certain kinds of stock and particularly envelops, I find it expedient to turn them over after the powder is made to adhere to the lettering carried by them. I will now describe the mechanism used for turning such pieces of stock.

The cam 170, carried by the drum shaft

37, is engaged by a cam pin 171, the latter being mounted upon a rod 172, and this rod being slidably mounted in bearings 173, as may be understood from Fig. 2. The rod 172 carries two nuts 174, 175, and located 70 between these nuts is an arm 176 mounted upon a pivot 176^a and provided at its lower end with an eye 177, through which a portion of the rod 172 extends.

The arm 176 carries at its upper end an eye 178, and extending through this eye is rod 179. Encircling this rod is a small slide 180, which is pivotally mounted upon the upper end of an arm 181. This arm is rigidly mounted upon a shaft 182, extending 75 across the machine and journaled in bearings 183. Loosely encircling the rod 179 is a ring 184, this ring being secured to a spring 186 which also encircles the rod. The spring is secured to a nut 185. Mounted 80 upon the shaft 182 are a number of spring fingers 187, each provided at its outer or free end with a hook 187^a, as indicated more particularly in Fig. 15.

The sprocket chains 43 coact with the 90 mechanism used for turning the piece of stock, and for this purpose are provided with projecting bosses 189. A piece of stock to be turned—in this instance, an envelop—is shown at 188 in Fig. 15. As the piece 95 of stock is carried along by the bands 39 and sprocket chains 43, the piece of stock rests with one of its edges against a pair of bosses 189, as indicated in Fig. 15. As soon as the opposite edge of the piece of stock reaches the hooks 187^a, the springs 187 are 100 swung upwardly by a rocking movement of the shaft 182, and as this occurs the travel of the bosses 189 causes the piece of stock to be turned bodily over, after which it continues its travel until it reaches its jogging board 45. The rocking movement of the shaft 182 is accomplished as follows: the 105 sliding movement of the rod 172, in the general direction of its length, causes the arm 176 to rock upon the pivot 176^a, and this movement of the arm 176 causes the rod 179 to move in a direction of travel approximately contrary to that of the rod 172. At 110 first the rod 172 slides freely through the eye 177, but when the nut 175 lodges against this eye the arm 176 begins its rocking movement upon its pivot. Whenever the rod 179 is thus moved to the left, according to Fig. 2, the ring 184 carried by the spring 115 186, lodges against the slide 180 and thus turns the arm 181, causing the shaft 182 to rock in a contraclockwise direction according to Fig. 2. This causes the rocking of the shaft 182, and in so doing causes 120 the envelop to be turned during its travel. The reverse movement of the rod 172 restores the shaft 182, with its spring fingers 187, to their respective normal positions.

By disconnecting the arm 176 from the 125

rods 172 and 179, the shaft 182 may be turned by hand so as to swing the spring fingers 187 upwardly and backwardly, so that their own weight together with that of the arm 181 and parts carried thereby, will maintain the spring fingers 187 inactive for the time being.

For preventing premature travel of the sheets of stock after they are carried up and left resting upon the rollers 56, I provide dogs 190, which are simply pendant weights adapted to hang or rest against the adjacent edge of the stock, said dogs hanging from the front of frame 61 that supports the powder container, and are shown in Fig. 4. The mere travel of the bands 39 is insufficient to disengage the sheets of stock from the dogs just mentioned, but when the bosses 189 (see Fig. 15) engage the stock and carry it forward by positive pressure, the dogs simply swing out of the way.

The operation of my device may be readily understood from the foregoing description. The various parts being constructed, arranged and assembled, as above described, and the machine being brought into communication with a printing press, as indicated fragmentarily in Fig. 1, the air pump is started into action, the burners are lighted, and the various adjustable parts are suitably adjusted.

The operator now passes the sheets, envelops, or other pieces of stock into and out of the printing press, and as each piece of stock is removed from the press it is laid upon the bands 47 of the conveyer 46. The travel of the bands 47 carries the piece of stock from the printing press 16 until it rests upon the rollers 56. The rollers carry the piece of stock onward in a horizontal direction, so that the piece of stock lodges against the guides 57. Here it stops, until engaged upon its lateral edge by bosses 189, whereupon it begins to travel in the general direction of the embossing machine. The rollers 56 are held above tapes 39, 39^b by their bearings so that the rollers receive the sheets from the bands 47 and carry them to the opposite side of the conveyer and up against guide 57, which is still higher than the rollers; when each cross rod of the conveyer carrying the bosses 189 comes to the guide 57 such rod passes up and on for its entire length (see Fig. 2) and carries the sheet with it and then drops back to its normal level. Passing under the dogs 190 as above described, the sheet next travels beneath the container. Here a small charge of the fusible powder drops from the container upon the sheet, as above described. Compressed air is next blown upon the sheet, and removes all excess of the powder—that is, so much of the powder as does not actually adhere to the ink of the printing letters. The excess of powder thus re-

moved enters the funnel 158, and is thence drawn by suction into the upper portion of the container.

At the beginning of the operation a suitable supply of the powder within the container is transferred into the lower compartment thereof, which is done by displacing the slide 71 slightly, and then pushing the slide back into its normal position. As the powder thus transferred into the lower compartment of the container is used up, more of the powder is let down from the upper compartment.

The sheets next pass along and, in the case of envelops, are turned over as above described. The sheets next pass over the burners, and are heated momentarily. The fusible powder adhering to the printed letters, being thus acted upon by the heat, causes the letters to practically swell, and stand out in relief, as if projecting slightly from the face of the paper. The sheet, thus finished has substantially the same appearance as if it had been subject to pressure in a press used for embossing. The finished sheets are finally discharged into the jogging board, where they are turned up or brought into exact registry.

While in this instance I show a gas burner for furnishing the heat required, it will be understood that I may employ any other heating means for the purpose. It will also be understood that various other portions of the mechanism described may be varied without departing from the spirit of the invention.

The purpose in constructing the lower part 64 of 63 in a single piece of resilient sheet metal is to form a self-closing bottom so that when necessary to get access to the feeding mechanism, the lower portion 64 can be lifted out of hopper 65 off the wedges 67 whereupon the resiliency of the sheet metal causes the slot 66 to immediately close and the part 64 can be lifted out with the contained powder.

Having thus described my invention, what I claim as new and desire to secure by Letters Patent is as follows:

1. An embossing machine comprising a frame, a conveyer journaled upon said frame and adapted to rest partly upon the feed board of a printing press, means for removing a printed sheet from said conveyer and for causing said sheet to travel along after leaving said conveyer, means for changing the direction of said sheet while in the act of being thus carried along, a powder container, mechanism coacting with movements of the sheet for causing the fusible powder to adhere to printed letters upon the sheet, heating mechanism for raising the temperature of said sheet in order to affect said fusible powder, and means for turning said sheet in order to expose

the lettering thereof to the direct action of the heat.

2. In an embossing machine, the combination of means for causing a printed sheet to travel bodily along, a powder container disposed adjacent to the path of travel of said sheet, a slide for opening and closing said powder container, means for periodically actuating said slide in order to discharge measured quantities of powder from said container upon said sheet, means for directing an air current upon said sheet in order to remove therefrom any excess of said powder, and heating means for said sheet.

3. In an embossing machine, the combination of means for supporting a printed sheet and for carrying said sheet bodily along a predetermined path, a powder container located adjacent said path and provided with an opening for discharging a powder, a slide movable relatively to said container and provided with an opening for discharging quantities of powder passing through said opening of said container, means for periodically actuating said slide in order to cause a periodical discharge of powder upon the sheet, pneumatic mechanism for blowing a current of air upon said sheet in order to remove any excess of powder resting thereon, and vacuum mechanism connected with said container for transferring thereinto the excess of powder thus removed from said sheet.

4. In an embossing machine, the combination of means for carrying a printed sheet along a predetermined path, a powder container disposed adjacent to said path and provided with an upper compartment and with a lower compartment, means for periodically opening and closing said lower compartment in order to control the discharge of powder therefrom upon said sheet, means for removing excess of powder from said sheet and for transferring said excess of powder into said upper compartment of said powder container, and means controllable at the will of the operator for transferring powder from said upper compartment of said container into said lower compartment thereof.

5. In an embossing machine, the combination, with means for supporting and moving a printed sheet along a predetermined path of travel, of a powder container with an upper compartment and with a lower compartment, a slide extending between said upper compartment and said lower compartment and serving as a partition for separating said compartments, the lower compartment having an automatically self-closing lower end, said slide being movable at the will of the operator for the purpose of discharging powder from said upper compartment into said lower compartment, and

means for periodically discharging powder from said lower compartment.

6. In an embossing machine, the combination of means for supporting a freshly printed sheet and for carrying the same along a predetermined path of travel, a powder container, a hopper for supporting said powder container, a slide movably connected with said hopper and provided with an opening for discharging quantities of powder passing into said hopper from said container, means for intermittently feeding said quantities of powder from said container into said hopper and upon said slide thereof, said intermittent feed mechanism being 80 geared to said slide, means for removing from said sheet so much of said powder as fails to adhere to the printed surface of said sheet, and means for heating said sheet after such excess of powder is removed.

7. In an embossing machine, the combination of means for supporting a freshly printed sheet and for carrying said sheet along a predetermined path of travel, a powder container provided with an opening, 90 said opening being disposed adjacent said path of travel, intermittently operated feed mechanism for discharging quantities of said powder from said powder container, a slide coating with said feed mechanism and adapted to intermittently discharge quantities of powder fed through said feed mechanism, gearing coating with said feed mechanism for periodically actuating the same, means for removing so much of said powder as fails to adhere to said printed surface of said sheet, and means for heating said sheet after it passes away from said powder container.

8. In an embossing machine, the combination of means for supporting in a flat condition a freshly printed sheet and for conveying the same along a predetermined path of travel, powder discharging mechanism for throwing a charge of powder upon said sheet, pneumatic mechanism for removing so much of said powder as fails to adhere to said sheet, and coating controllable mechanism connected with said powder-discharging mechanism and said pneumatic mechanism for periodically actuating the same in unison.

9. In an embossing machine, the combination of means for supporting and conveying a freshly printed piece of stock, powder depositing mechanism for discharging powder upon said piece of stock, in order to cause portions of said powder to adhere to a printed surface of said piece of stock, mechanism for forcing a current of compressed air against said surface in order to remove all portions of said powder failing to adhere to said surface, and means for heating said piece of stock in order to fuse and harden said portions of powder adhering to 130

said printed surface after removal of the surplus powder.

10. The combination of means for supporting a freshly printed piece of stock, means for discharging fusible powder upon said piece of stock, so as to cause portions of said powder to adhere to the printed portions, pneumatic mechanism for forcing compressed air against said piece of stock, 10 in order to remove those portions of powder which fail to adhere to said printed surface, vacuum mechanism coacting with said pneumatic mechanism for displacing and hous-

ing the portions of said powder thus removed from said surface, and means for heating said piece of stock in order to cause said powder to fuse and harden after such removal of the surplus powder. 15

In testimony whereof I have signed my name to this specification in the presence of 20 two subscribing witnesses.
